UNITED STATES PATENT OFFICE.

LEVI LUNDQUIST, OF MIDDLETOWN, CALIFORNIA.

GRAFTING-VALVE.

1,380,992.

Specification of Letters Patent. Patented June 7, 1921.

Application filed July 12, 1920. Serial No. 395,478.

To all whom it may concern:

Be it known that I, LEVI LUNDQUIST, a citizen of the United States, residing at Middletown, in the county of Lake and

5 State of California, have invented certain new and useful Improvements in Grafting-Valves, of which the following is a specification.

This invention relates to the art of grafting and has as its general object to provide 10 a novel and simple means for controlling the flow of sap from the stock after the shoots have been grafted thereto.

Heretofore it has been customary, after 15 selecting the stock, to cut off the upper portion thereof, make the required number of incisions or clefts in the upper end of the stock at suitable points in its circumference, graft the shoots in place, and then apply 20 over the upper end of the stock and over the grafted ends of the shoots a coating of a suitable grafting wax so as to prevent drying out of the stock through evaporation of the sap bleeding therefrom. It has been found, 25 however, that if a considerable quantity of sap accumulates beneath the wax coating, the coating will be lifted and will be caused to burst or crack thus admitting air with the result that the sap is soon dried out and the 30 growth of the grafts is either greatly retarded or ceases altogether. Therefore the primary object of the present invention is to provide a device acting in the manner of a valve to allow for the overflow of surplus 35 sap from the stock and yet at the same time prevent access of air to the stock beneath the coating of wax in any quantity sufficient to cause any appreciable drying out of the sap. Incidentally the invention has as its 40 object to provide a device for the purpose stated which, inasmuch as it permits of overflow of the surplus sap, will prevent the accumulation of sap beneath the wax coating to such an extent as to cause the coating 45 to burst or crack and thus admit air to the stock with the disastrous results above stated.

Another object of the invention is to provide a device of the class described which 50 may be manufactured at an extremely low cost and which may be readily employed for the purposes above stated without the use of any special tools and without requiring any particular attention after it has once 55 been placed in position.

In the accompanying drawings:

Figure 1 is a perspective view illustrating the manner of employing the device embodying the invention;

Fig. 2 is a view in elevation of the device 60 in use, the stock and wax coating being shown in section;

Fig. 3 is a similar view taken in a plane substantially at right angles to the plane 65 of Fig. 2;

Fig. 4 is a detail perspective view of the grafting valve.

In the drawings the numeral 1 indicates the stock to which the shoots are to be grafted, the shoots being indicated by the 70 numeral 2. In grafting the shoots, the usual method of cleft grafting is resorted to, the required number of shoots being placed at suitable points about the circumference of the upper end of the stock 1. 75 However, after the shoots have been grafted to the stock and before the wax coating which is customarily employed, is applied, the device embodying the present invention is driven into the stock. The said device is 80 most clearly illustrated in Fig. 4 of the drawings and is as before stated in the nature of a valve and is indicated in general by the numeral 3. The valve comprises a cylindrical tubular body 4 having one end 85 5 disposed at right angles to its axis. The other end of the body 4, however, is cut diagonally as indicated by the numeral 6 so as to provide a laterally facing opening 7 at the lower portion of the body and a 90 pointed terminal 8 at the said end. As above stated, the device of the invention is applied after the shoots have been grafted to the stock but in any event, in applying the device, its pointed lower end will be 95 driven into the upper end of the stock with a hammer or any other driving implement, the pointed terminal 8 adapting the device to readily enter the stock and become firmly embedded therein. The distance to which 100 the device is driven into the stock may be varied at the judgment of the user but in any event the valve will not be driven in so far as to completely close the opening 7 so that the upper portion of this opening will 105 lie above the upper end of the stock in the manner most clearly shown in Figs. 2 and 3 of the drawings. When the valve has been thus driven into place, a suitable quantity of raw cotton or other absorbent mate-

110

rial, indicated by the numeral 9, is packed within the valve through the upper end thereof so as to fill the exposed portion of the opening 7 but not so compactly as to interfere with free absorption of sap by the filling. After this absorbent filling has been lightly pushed down into the valve until it touches the top of the stock, the usual coating 10 of any suitable grafting wax is applied to the stock to cover the upper portion and upper end thereof and the lower end portions of the grafts or shoots. This coating 10 also is packed about the projecting upper end portion of the valve 3 in such manner as to completely cover the absorbent material exposed in the opening 7, but the coating does not extend over or in any way obstruct the open upper end of the valve.

20 After the valve has been packed, it requires little if any further attention.

From the foregoing description it will be understood that any surplus sap bleeding from the stock 1 and which would otherwise accumulate beneath the coating 10 and cause the coating to bulge and burst or crack, will, due to the presence of my invention, be absorbed by the filling 9 within the valve and, passing through the opening 7, will accumulate within the valve and may overflow at its upper end without any likelihood, however, of air passing down through the filling to the stock. Thus the stock is protected from air and there is no likelihood of its drying out and thus retarding or completely stopping the growth of the grafts.

It will be evident from the foregoing that the invention resides not alone in the means which I have provided for the overflow of surplus sap from the stock but also in the

method of providing for this overflow, this method consisting in providing an overflow leading through the coating of grafting wax and in further providing within the overflow a packing to absorb the sap and exclude air 45 from the stock.

In walnut grafting a strip of cloth should be wrapped around the waxed stock and upper edge folded over and a paper bag tied over it protecting the scions from the sun 50 and drying winds. The tops of the bag are cut out when scions start to grow.

Having thus described the invention, what is claimed as new is:

1. A grafting sap valve comprising a 55 member having a cavity to receive a packing of absorbent material and provided with a passage for the entrance of the sap and communicating with the said cavity.

2. A grafting sap valve comprising a tubular member having an entering end cut diagonally whereby when the said end is driven into the stock for a portion of the length of the said end only, an opening will be left in the side of the valve through which 65 sap may enter the valve.

3. A grafting sap valve comprising a tubular member having one end substantially at right angles to its axis to provide for direct blows being struck thereagainst with a 70 driving implement and having its other end cut diagonally to provide a tapered entering portion, whereby when the entering portion is driven into the stock for a portion of the length of the entering portion only, 75 an opening will be left in the side of the valve through which the sap may enter the valve.

In testimony whereof I affix my signature.
LEVI LUNDQUIST. [L.S.]
